DESIGN FOR A TRICYCLE

Le Roy W. Sly, Kyburz, Calif.

Application March 12, 1945, Serial No. 118,410

Term of patent 3½ years

(Cl. D90—8)

To all whom it may concern:

Be it known that I, Le Roy W. Sly, a citizen of the United States, residing at Kyburz, in the county of El Dorado and State of California, have invented a new, original, and ornamental Design for a Tricycle, of which the following is a specification, reference being had to the accompanying drawing, forming a part thereof.

I claim:

The ornamental design for a tricycle, as shown.

LE ROY W. SLY.
